UNITED STATES PATENT OFFICE

JOHN E. DOLDT, OF PORTLAND, MAINE, ASSIGNOR TO THE DOLDT FARE HANDLING MACHINE COMPANY, OF PORTLAND, MAINE, A CORPORATION OF MAINE.

FARE-COLLECTION SYSTEM.

Application filed June 9, 1920. Serial No. 387,574.

To all whom it may concern:

Be it known that I, JOHN E. DOLDT, a citizen of the United States, residing at Portland, in the county of Cumberland and State of Maine, have invented certain new and useful Improvements in Fare-Collection Systems; and I do hereby declare the following to be a full, clear, and exact description of the invention, such as will enable others skilled in the art to which it appertains to make and use the same.

The present invention relates to apparatus employed in connection with a zone system of fare collection.

There are certain obvious advantages in connection with the use of a zone system upon railway systems handling city and suburban traffic in which the length of haul may vary markedly. Perhaps the most important advantage attendant upon this type of system is the fact that it enables a charge to be made according to the distance which the passenger travels so that the short haul passenger is not required to pay a fare sufficient to cover the expense of handling the long haul passenger.

The present invention is more particularly adapted to form a part of that class of zone systems in which the fare of the passenger is computed and paid upon leaving the car at the passenger's destination, but may be employed in connection with the collection of fares when the passenger boards the car, as for example in the case of a short trip where the travel of the passenger cannot possibly exceed two or three zones and a minimum fare must be paid in any event.

One object of the invention is to provide an improved form of system which facilitates the computation and collection of the requisite fare according to the number of zones through which the passenger has or will travel to his destination. A further object of the invention is to provide a system which shall employ tokens or tickets indicating the zone at which the passenger boarded the car, these tickets being indestructible and capable of being used over and over for an indefinite period.

A still further object of the invention is to provide improved apparatus for distributing the proper tokens or tickets at each zone and for collecting these tokens in the proper receptacles at the point of destination.

With these objects in view the several features of the invention consist in the novel features of construction, combinations and arrangements of parts hereinafter described and claimed, the advantages of which will be obvious to those skilled in the art from the following description.

In the accompanying drawings illustrating the preferred form of the invention Fig. 1 represents an elevation of the distributing and collecting apparatus designed to be actuated by a single operator; Fig. 2 is an elevation of the token distributing apparatus; Fig. 3 is a top plan view of the distributor shown in Fig. 2; Fig. 4 is an elevation of the collecting apparatus; Fig. 5 is a top plan view of the collecting apparatus shown in Fig. 4; Fig. 6 is a detail showing a section on the line 6—6 of Fig. 5; and Fig. 7 is a collective view of the various tokens employed in the system.

The present invention comprises a token distributing apparatus which contains tokens or tickets corresponding to the zones through which the route of the car passes. The distributing apparatus is actuated to cause the delivery of the proper token for the particular zone through which the car is passing and when each passenger boards the car a token is delivered corresponding to the zone in which the car is then located. The delivery of this token is recorded by a suitable mechanism in order that a record may be kept of the total number of tokens delivered within a given period. Associated with the token distributing mechanism is a token collecting mechanism in which the token is adapted to be deposited upon arrival at the destination of the passenger. According to the usual operation of the apparatus, the passenger, upon arriving at the destination, shows the conductor the token indicating the zone at which the car was boarded and the conductor then collects the

proper fare for the zones through which the passenger has traveled, the zone token being thereafter deposited by the passenger in the collection apparatus. The collection apparatus, in addition to containing at the end of the day's run all of the zone tokens which have been deposited by passengers, indicates the number of zones through which each passenger has traveled, together with the number of passengers boarding and leaving the car during each trip. This not only facilitates checking the fares collected by the conductor but in addition affords an accurate indication of the volume of travel over any particular portion of the transportation system and the approximate time at which this travel took place.

In the illustrated embodiment of the invention a token distributing apparatus is indicated generally at 10. This apparatus, as shown in Fig. 2, comprises a series of token stacks 12 corresponding in number to the number of zones through which the route of the car passes. In the present construction twelve of these stacks are illustrated. Each of the token stacks contains a pile of metal tokens such as are indicated at 13 in Fig. 7, the tokens in each stack indicating a particular zone. These stacks are held at top and bottom between two revolving rings 15 and 16 which are received in annular recesses formed in top and bottom plates 17 and 18 connected by a centrally disposed post 19. The base plate 18, as indicated clearly in Fig. 2, is provided with a token delivery cup 20 depending from beneath the plate. Whenever a passenger boards the car, a token is ejected from the bottom of the pile into the cup 20 by the person operating the distributing apparatus. This delivery of the token is accomplished through a lever 24 fulcrumed centrally upon a bracket 25 which is secured to the post 19. The lower end of the lever 24 projects into a slot formed in a sliding ejector plate 26 which is adapted to engage the bottom token of a pile and push the coin sidewise into position above an opening 27 through which the coin drops into the delivery cup 20. During the ejection of the token from the bottom of the pile it engages with the lower end of a swinging arm 30 which is connected with any suitable form of register 31 through an arm 32 and connecting link 33. This register is designed to record the total number of tokens which are delivered to passengers. After the lever 24 has been actuated to deliver a single token from the bottom of the pile it is returned, together with the ejector plate, to initial position through a spring 28 interposed between the lever and the post 19 above the fulcrum of the lever. As will be evident, the upper portion of the lever projects through a slot 38 formed in the upper head

17 into a position where it is conveniently accessible for manipulation by the operator. In order to cause the delivery of a token corresponding to the zone through which the car is passing, the rings 15 and 16, together with the token stacks are revolved intermittently as the car progresses throughout its route, this revolving movement advancing the stacks to present a new stack in position for the delivery of tokens as each new zone is entered. To this end, each ring is provided with gear teeth 34 and 35 which are respectively engaged by driving pinions 36 and 37 mounted upon a post 39 provided at its top with an operating handle 44 which is normally retained in the position shown in Figs. 2 and 3 by a spring pressed detent 45 engaging a corresponding recess formed in the underside of the handle. The gears are so designed that one complete rotation of the handle rotates the stacks a sufficient distance to move the next adjacent stack into position for the delivery of the tokens so that thereafter as the lever 24 is actuated tokens are delivered to the passenger, corresponding to the zone at which the car is boarded. It will be observed upon referring to Fig. 2 that the bottom of each stack is provided with a transverse slot 46 through which the ejector plate 26 may pass and that only when the stacks are properly located can a token be delivered by the plate 26. In the illustrated embodiment of the invention it will be observed that the stacks are numbered consecutively, corresponding to the several zones, and each numbered stack contains a pile of correspondingly numbered tokens. Thus during the travel or the passage of the car through zone 8, all passengers boarding the car receive tokens correspondingly marked, but upon the passage of the car into zone 9 the stacks are advanced to bring stack No. 9 into delivery position and thereafter passengers boarding the car in zone 9 receive tokens correspondingly marked. In order to apprise the passengers of the delivery of the tokens and insure that they shall be taken by the passenger it is desirable to provide some form of indication.

To this end a bell 50 is mounted upon the shaft 18 through a bracket 52 and is provided with a rotary striker 53 adapted to be operated from the lever 24 through a rack arm 55 and connected gears 56 and 57. Thus upon each actuation of the lever 24 to deliver a token to the cup 20, the bell is operated to indicate the fact to the passengers. Located at the top of each pile of zone tokens is a marker token, indicated at 60, Fig. 7, which is somewhat thicker than the zone tokens 13 and is incapable of being ejected through the slots 46 and the bottom of the stacks. This marker token indicates to the operator that the pile of tokens in the

stack is exhausted and also shows in relation to the graduations upon the stack tubes the number of tokens in each stack that have been distributed. In addition, each stack is 5 provided with a series of perforations or openings 62 through which the operator may observe the number of tokens remaining in the stacks. According to the usual practice the stacks of the delivery mechanism will 10 be filled with the necessary number of tokens at the beginning of the day's run and will not require replenishment until the car returns at night.

When the passenger leaves the car, the 15 operator inspects the zone token delivered to the passenger upon boarding the car. With this information the number of zones through which the passenger has traveled is readily ascertained and the fare computed. 20 For example, if the passenger boards the car in zone 3 and leaves the car in zone 8, a fare will be paid for travel through six zones, which total number of zones includes the zones at which the car is boarded and 25 left, together with the zones through which the passenger traveled completely. After the fare has been computed and paid to the conductor, the passenger deposits his zone token in the collecting mechanism which 30 then delivers the token to a numbered stack corresponding to the zone through which the car is then passing. The collecting mechanism is similar to the distributing mechanism in that it comprises a number of 35 stacks corresponding to the zones through which the car passes and is operated by the conductor or other authorized person to present each stack in proper position according to the zone through which the car 40 is passing.

Referring to Figs. 4 and 5 of the drawings, the collecting mechanism is indicated generally at 65 as provided with a series of token stacks 67 held at top and bottom between revolving rings 68 and 69 which are journaled in top and bottom plates 70 and 71, respectively, connected by a centrally disposed vertical post 72. Each of the rings 68 and 69 is provided with gear teeth 74 and 75 which are engaged by gears 77 and 78 mounted upon an operating shaft 80 provided with a handle 82 which is journaled in extensions of the top and bottom plates 70 and 71. The collecting mechanism is 50 provided with a suitably disposed tray 90 in which the tokens are deposited. The tray is connected with an inclined delivery chute 91 which discharges the token into a temporary deposit magazine 92 closed at its bottom by a supporting plate 93. The inclined chute is provided with a ledge 94 along one side, which supports the token in an angular position with respect to the bottom of the chute which is provided with an 55 elimination opening 96 through which coins

or pieces of metal smaller than tokens will drop. This is due to the fact that coins smaller than the tokens lie in the groove formed between the ledge 94 and the opposite edge of the chute. The tokens after 60 collection in the deposit magazine are transferred by means under the control of the operator to the proper containing stack. To this end a transfer arm 100 is fulcrumed upon the shaft 72, as shown in Figs. 4 and 5, 65 and is provided with a curved end 101 adapted to engage behind the token and sweep the token over the supporting plate 93 in a curved path. Upon referring to Fig. 5 it will be observed that the curved 70 face 103 of the transfer arm is designed to constantly press the token against the inner edge 104 of the curved track of which the plate 93 forms the bottom. This plate is provided with an elimination opening 105 75 (Fig. 6) through which a coin or article smaller than a token will drop and be removed from the machine, if such a metal article should traverse the complete length of the chute. During the passage along the 80 curved track, by means of the transfer arm, the token, as indicated in Fig. 6, engages a swinging finger 107, the lower end of which depends into the path of the token. This finger is connected through a shaft 108 with 85 any form of registering device 109 which keeps a record of the total number of tokens deposited and collected in the apparatus. Upon referring to Fig. 4 it will be observed 90 that the inclined chute 91 and receiving hopper 90 are conveniently supported upon a vertical post 110 which rises from the upper head 70 of the machine. After its passage by the swinging finger 107, the token is delivered to an opening 112 (Fig. 6) which 95 registers with the upper end of a token stack 67. It will be evident that through the instrumentality of the operating handle 110 100 and connected mechanism, the token stack which is positioned beneath the opening 112 at any given instant is numbered in accordance with the zone through which the car is then passing. In order to accomplish this the operator will move the handle of each apparatus one complete turn when the 105 car passes from one zone into the next.

It is desirable to employ some means for determining at the end of the day's run during which trips of the car the tokens were deposited, thus affording an accurate 110 indication as to the number of passengers leaving the car in each zone during each trip and affording a basis for computing the average length of haul, the time of day during which the greatest travel took place, 115 and other facts which are essential in the computation of fares. To this end a stack or tube 115 is supported upon the upper head 70 and is filled with trip tokens such as are indicated at 116 in Fig. 7. These 120 125 130

trip tokens are delivered individually to the opening 112 and from there pass into a token stack each time that a new stack is brought into position beneath the opening. 5 To this end a sliding delivery plate 118 is mounted upon the top of the head 70, as shown in Fig. 5, and passes beneath the tube 115, engaging the bottom-most token and ejecting it at each transverse movement. 10 This delivery plate is connected with the shaft 80 through a gear 120 mounted upon the shaft and a cooperating gear 121 journaled upon the upper face of the head 70. The gear 121 is provided with an eccentrically disposed pin 122 which moves in a transverse slot 123 formed in the delivery plate 118, the construction being such that one complete reciprocation is imparted to the delivery plate for each complete rotation 15 of the shaft 80 to advance the revolving stack turret one step. This serves to initially deposit a trip token in each stack as it is brought into position beneath the opening 112 and before the deposit therein of any 20 zone tokens for that trip. It will be evident that with this construction at the end of a day's run each of the collecting stacks will contain a different series of zone tokens, each group being separated by a trip token, the 25 number of zone tokens in each group indicating the number of passengers leaving the car in one trip and the zone tokens in each stack indicating the total number of passengers leaving the car in that particular zone 30 during the total number of runs for that particular stack. Aside from indicating the travel in the different zones the trip tokens are also an important check to prevent improper manipulation of the collecting device 35 by the operator.

It is very desirable that some means be provided for facilitating the computation of fares by the conductor or other person in charge of the collecting apparatus. To this 40 end the present invention contemplates the employment of relatively movable members which indicate respectively zones and fares. In the simplest and most efficient form of the invention which has yet been devised, a 45 stationary fare indicator is employed in conjunction with the revolute turret carrying the token tubes. As will be evidenced from an inspection of Figs. 1 and 4, the stationary bottom plate 71 of the collecting mechanism 50 is provided with two sets of indications upon its periphery, each set of indications registering with one of the tubes of the revolute turret. In the specific form of the invention illustrated, the passenger will pay a minimum fare of five cents for either one or two 55 first zones traveled and thereafter an increased fare of two cents for each additional zone. When the car is passing through zone 60 1 with the stack numbered 1 in receiving position the relative arrangement of token

tubes and the upper set of fare indications will be as follows, the upper row of figures representing the numbers upon the token tubes and the lower row representing the fare amounts:

1 2 3 4 5 6 7 8 9 10 11 12
05 25 23 21 19 17 15 13 11 09 07 05

Upon passing from zone 1 to zone 2, the 70 turret is actuated so that tube 2 takes the place of 1; 3 takes the place of 2; while 1 takes the place of 12. Similarly as the car passes through successive zones the correspondingly numbered tube will advance to the position originally occupied by tube 1. 75 When, for example, the car is passing through zone 8 tube 8 is in position to receive the tokens, this being the position illustrated in the drawings. The relation between the tube numbers and the fare 80 amounts will then be as follows:—

8 9 10 11 12 1 2 3 4 5 6 7
05 25 23 21 19 17 15 13 11 09 07 05

A passenger who leaves the car in zone 8 85 shows the token to the conductor and then deposits it in the distributing mechanism where it is received and segregated in tube 8. The conductor then looks under the tube 90 numbered in accordance with the passenger's 95 token and reads the fare amount. For example, if a passenger boarded the car in zone 4 and left the car in zone 8, the conductor, upon observing the zone token numbered 4 and referring to the position of the 100 token tube numbered 4, could immediately determine that the fare to be paid was eleven cents, as indicated by the upper set of figures upon the rim of the bottom plate 71. The second set of figures upon the bottom 105 plate is arranged to increase numerically in the opposite direction from the upper set and is intended for computing the fares when the car is traveling in the opposite direction, the computation being made in 110 the same manner as above described, as will be clearly obvious to those skilled in the art.

In order to indicate to the passengers the zone through which the car is traveling, the operating shafts upon both the collecting 115 and distributing mechanisms are provided with extensions 130 which operate through any suitable system of gearing, not shown, zone indicators 131 to show visually the zone through which the car is then passing. It 120 will be evident that when each of the operating handles is rotated to advance a new stack into position the extension shaft 130 will operate the indicators to correspond to the token stack which is in operative 125 position.

While the present system of fare collection has been described more particularly in connection with fare apparatus actually located upon the moving car, it should be 130

understood that the invention as a whole is not limited to such a use but can be embodied to advantage in elevated or subway systems where the distributing and collecting apparatus would be located in the several stations and operated by a person in the station, relieving the operators of the cars from all labor of such fare collection.

5 While it is preferred to employ the specific 10 construction and arrangement of parts shown and described, it will be understood that this construction and arrangement is not essential except so far as specified in the claims, and may be changed or modified 15 without departing from the broader features of the invention.

The invention having been described, what is claimed is:

1. Fare collection apparatus comprising 20 distributing mechanism having a plurality of numbered tubes, permanent zone tokens contained in each tube and numbered in accordance with the tube, means for delivering a token to a passenger corresponding 25 to the zone through which the car is passing, a collecting mechanism provided with a plurality of similarly marked tubes, and means for receiving and segregating the token in the tube corresponding to the zone through 30 which the car is passing.

2. A fare collection apparatus comprising means for delivering to a passenger a permanent zone token corresponding to the zone at which the car is boarded, and means including a series of receptacles marked in accordance with the different zones for receiving and depositing the permanent zone token when the passenger leaves the car.

3. A fare collection apparatus comprising 40 a series of zone token delivery tubes and a series of zone token collecting tubes, means for causing the delivery of a permanent token according to the zone through which the car is passing, and means for causing 45 the deposit of the permanent token in a collection tube corresponding to the zone through which the car is passing.

4. A fare collection apparatus comprising 50 token distributing apparatus constructed and arranged to deliver to a passenger a permanent token corresponding to the zone through which the car is passing, and token collecting apparatus constructed and arranged to receive and deposit the permanent token according to the zone through which 55 the car is passing when the token is deposited in the apparatus.

5. Fare collection apparatus comprising 60 a plurality of tubes marked in accordance with the zones through which the car passes, a pile of permanent zone tokens contained in each tube, a revoluble turret upon which the tubes are mounted, means for moving a token from one of the tubes to deliver it 65 to a passenger, and means for shifting the

position of the tubes to bring successive tubes into operative position with respect to the token moving means as the car passes from one zone to another.

6. Fare collection apparatus comprising a 70 token distributing mechanism and a token collecting mechanism each provided with a plurality of similarly marked tubes, each tube being adapted to contain permanent tokens, and means for moving the tubes to 75 bring successive tubes into operative position as the car passes from one zone to another.

7. A fare collection apparatus comprising a series of token containing tubes, a revoluble turret carrying the tubes, means 80 for revolving the turret to bring successive tubes into operative position, a token receiving tray, and means for transferring tokens from the tray to a final collection tube which is located in operative position. 85

8. Fare collection apparatus comprising a plurality of token tubes, means for moving the tubes to bring a new tube into operative position when the car passes from one zone to another, and means for depositing a single 90 trip token in the tube which is being moved into operative position.

9. A fare collection apparatus comprising a series of tubes adapted to contain zone tokens, a tube containing trip tokens, means 95 for shifting the zone token tubes to bring successive tubes into operative position, and means connected therewith for simultaneously delivering a single trip token from the containing tube to the zone token tube 100 which is moved into operative position.

10. A fare collection apparatus comprising a series of token containing tubes, a token deposit magazine, means for transferring tokens from the magazine to one of 105 the tubes, and means for diverting coins or other articles of less diameter than the tokens from the apparatus prior to delivery to the containing tube.

11. A fare collection apparatus comprising 110 a series of token containing tubes, a deposit magazine, a transfer arm adapted to transfer a token from the magazine to one of the tubes, means for recording the number of tokens thus transferred, and means for diverting coins or other articles of less diameter than the tokens prior to engagement with the recording mechanism.

12. A fare collection apparatus comprising 115 two relatively movable members, one being provided with consecutive indications showing the number of zones through which a car travels and the second being provided with the amount of fare to be collected, and means for imparting a relative step by step movement to the members to bring successive zone indications opposite different fare amounts.

13. A fare collection apparatus comprising 125 a stationary member, a rotating mem-

ber, a series of fare computations formed upon the stationary member, a series of zone indications formed upon the rotating member, and means for imparting a step by step 5 rotation to the member to bring successive zone indications opposite different fare amounts.

14. A fare collection apparatus comprising a revoluble turret carrying a plurality 10 of numbered tubes mounted upon the turret

and carried therewith, a stationary dial supported in proximity to the turret having a series of fare amounts indicated thereon in predetermined relation to one another, and means for imparting a step by step rotation 15 to the turret to bring successive numbered tubes opposite different fare amounts on the stationary dial.

JOHN E. DOLDT.
